UNITED STATES PATENT OFFICE.

WILLIAM TRABUE, OF LOUISVILLE, KENTUCKY, ASSIGNOR OF TWO-THIRDS
TO W. W. BARNES AND GUY C. SIBLEY, BOTH OF SAME PLACE.

SAW-SETTING DEVICE.

SPECIFICATION forming part of Letters Patent No. 398,357, dated February 19, 1889.

Application filed November 12, 1888. Serial No. 290,601. (No model.)

To all whom it may concern:

Be it known that I, WILLIAM TRABUE, a citizen of the United States, and a resident of Louisville, in the county of Jefferson and State of Kentucky, have invented certain new and useful Improvements in Automatic Saw-Sets; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of a perspective view of this invention. Fig. 2 is a side view of the same. Figs. 3, 4, and 5 are details of the construction.

This invention relates to improvements in automatic saw-sets; and it consists in the construction and novel combination of parts, as hereinafter set forth, and pointed out in the claims.

Referring by letter to the drawings, A designates the side plate having the bearings B in its transverse upper portion for the journals of the roller C, which has the annular cam-groove *a* therein. The said groove *a* has the opposite straight portions and the opposite cam or V shaped portions *b*, which are designed to throw the set-disk to the right and left, as hereinafter explained, when the said roller is revolved by means of a crank on the outer end of the extended journal *c*.

D is a guide-plate, between which and the inner face of the side plate, A, the saw-blade is designed to slide. The plate D has a threaded bolt, *d*, standing at right angles thereto and passing through an opening in the side plate, where it is engaged by a thumb-nut, E, having an annular flange, *e*, on its inner end engaging in the groove *f*, formed in the bracket F on the side plate, which prevents longitudinal movement of the nut, so that the nut turning on the screw will adjust the plate D to the thickness of the saw-blade.

G is a slide or bar, which is preferably graduated, seated and moving in a groove in the bed-plate H, which projects laterally from the lower edge of the plate D, and I is a collar or

yoke secured at any desired point on the bar G by means of the thumb-screw *g*, and having a rearward extension-piece, J, bearing closely against the edge of the bar G. A dog or pawl, K, is pivoted to the lug L, upstanding and integral with the bar G, designed to engage successively the teeth of the saw and move the instrument along the blade one tooth at a time. A spring, *h*, secured at one end to the lug L, holds the pawl in engagement with the saw-tooth.

M is a lever pivoted on the bar N', and having at its upper end the ring *j*, provided with the eccentric portion *k*, surrounding the journal *c*, which has the diametrically-opposite projections or lugs *l*, designed at every half-revolution of the journal to strike the eccentric *k* and throw the lower end of the lever forward, so that the pin M' thereon will strike against the end of the extension J and carry the setting-instrument along the saw by the engagement of the pawl of the slide with a tooth of the saw-blade, said blade being held in a vise. The coiled spring *n*, secured at one end to the bar G, and at its opposite end to the bed-plate H, returns the parts to their normal position when a lug *l* shall have passed the eccentric.

The collar I is adjustable on the bar G, and is designed to be set by the graduation-marks thereon to suit the length of the tooth of the saw on which the instrument is being operated. The slide-bar G and its pawl are moved by the collar according to the adjustment of the latter, and the collar is operated by the stroke of the lever M against the extension or portion K, whereby the stroke of the pawl is governed. After the stroke the slide-bar, operated by its spring, returns to position.

N designates a thrower-plate pivoted on the pin *o*, projecting from the side plate, A, and having a lug, *p*, at its upper end projecting into the cam-groove *a* of the roller C, so that when the roller is operated the plate N is reciprocated to carry the set-disk O, which is also journaled on the pin *q*, and secured to the plate N by means of the coupling-pin *r*, projected through an opening in said plate, and any one of the series of openings *s* in the disk that may be required to bring any one

of the series of set-notches *t* in the periphery of the disk to operate upon the saw-teeth. The said notches *t* are of different widths and properly numbered, so that the saw-teeth 5 may be set at the required angle.

It is evident that the revolving of the roller C will impart a vibratory motion to the set-disk, so that one side of the notch in engagement with the saw-teeth will set the tooth in 10 one direction, and the next tooth will be oppositely set when the opposite side of the notch comes in contact therewith, the blade being moved forward, as heretofore explained.

A height-guide, R, is provided with a slot-opening, *n*, to engage on the threaded bolt *v*, 15 extending from the bed-plate, so that it may be moved up or down to bring its inwardly-turned flange *w* to the height required to regulate the passage of the instrument over 20 the saw-teeth, it being held as adjusted by the thumb-nut *x*. The height-guide flange moves on the tops of the teeth as the instrument is fed along the blade and regulates the height of the instrument with reference to 25 the notch of the thrower-plate.

Having described my invention, what I claim is—

1. In a saw-set, the combination, with the crank, the cam on its shaft, and the pivoted 30 notched thrower-plate for setting the teeth, of the intermittently-operating lever, the feed-pawl, and the adjustable devices regulating its stroke, substantially as specified.

2. The combination, with the side plate 35 having the bearings, of the roller having the cam-groove, the pivoted plate N, having its end extended into said cam-groove, the pivoted set-disk, and the operating-crank, substantially as specified.

3. The combination of the side plate, A, 40 having the bearings, the roller journaled in said bearings and having the annular cam-

groove, the crank, the pivoted plate having the lug extended into the cam-groove, the pivoted set-disk secured to said plate, and the 45 guide-plate D, having the bolt extended through an opening in the side plate, substantially as specified.

4. The combination, with the side plate, A, 50 having the transverse bearing portion, the pivoted plate N, and the set-disk, of the roller having the cam-groove, the lugs on its extended journal, the pivoted lever M, having the eccentric within its ring end and the pin on its opposite end, and the graduated bar and the pawl 55 pivoted thereon, substantially as specified.

5. In combination with the bearing-plate A, the cam-groove roller, the pivoted plate engaging the pivoted set-disk, and the pivoted lever M, the graduated bar seated in the 60 grooved lateral bed-plate, the spring-controlled pawl pivoted to the bar, the yoke having the extension, the thumb-screw, and the returning spring, substantially as specified.

6. In a saw-set, the combination, with the 65 slide-bar, the intermittently-acting lever, and the operating mechanism, of the height-guide having the slot-opening and the inwardly-projecting portion, and the fastening-screw, substantially as specified. 70

7. In a saw-set, the combination, with a notched oscillating thrower-plate for setting the teeth, the adjustable height-guide, a slide-bar carrying a feeding-pawl, and an intermittently-acting stroke-lever, of a shaft having 75 a turning-crank, and carrying devices to operate said thrower-plate and lever, substantially as specified.

In testimony whereof I affix my signature in presence of two witnesses.

WILLIAM TRABUE.
